UNITED STATES PATENT OFFICE.

JAMES F. WAID, OF CINCINNATI, OHIO, ASSIGNOR OF ONE-THIRD TO CHARLES H. KRIPPENDORF AND ONE-THIRD TO WILLIAM FOWLER, BOTH OF CINCINNATI, OHIO.

MACHINE FOR TACKING THE SHOE UPPER AND COUNTER.

1,102,612

Specification of Letters Patent.

Patented July 7, 1914.

Application filed December 24, 1906. Serial No. 349,352.

To all whom it may concern:

Be it known that I, JAMES F. WAID, a citizen of the United States, residing at Cincinnati, in the county of Hamilton and State 5 of Ohio, have invented certain new and useful Improvements in Machines for Tacking the Shoe Uppers and Counters, of which the following is a specification.

My invention relates to a shoe upper tacking machine.

The object of my invention is to produce a machine which will gather the surplus and loose portions of the upper and counter at the inner ends of a heel-seat adjacent to the 15 ends of the welt, and push them in toward the medial line of the shoe and hold them there while they are tacked.

Hitherto, in making welt shoes, after the shoe came from the inseam stitcher and 20 welt trimmer, that portion of the heel-seat toward the shank of the shoe was comparatively loose. It was the custom to push the material in as well as possible and insert and drive a tack by hand. But with this method 25 the open ends of the heel-seat just adjacent to the ends of the welt were left so wide that they would spread, making a wide heel-seat, and in the subsequent operation of trimming the edge of the outsole, the cutter would run 80 into and sever the stitches at the shank of the last.

I have produced a machine to make the heel-seats narrow adjacent to the welt.

The features of the invention are more 35 fully set forth in the description of the accompanying drawings, forming a part of this specification, in which:—

Figure 1 is a side elevation of my machine. Fig. 2 is a front elevation of the 40 same. Fig. 3 is a top plan view, showing the juxtaposition of the nailing block and tucker.

1 represents the frame of the machine, 2 is the main driving shaft driven by pulley 3. 45 Shaft 2 is provided with cam mechanism, (not shown), operating bell crank lever 4.

6 represents an arm in the outer end of which is supported a nail driver 7 reciprocated by the bell crank lever 4.

50 8 represents a block for receiving the tacks and within which the driver reciprocates.

9 represents a hopper for holding the tacks, and 10 a chute for delivering them to the block 8.

55 11 represents a tack feed regulator recip-

rocated by means of an eccentric rod 12 operated from shaft 2. By means of this mechanism, which is of well-known type, the tacks may be fed one at a time to the nail block 8 and the tack driven when the machine is put into operation by treadle and clutch mechanism, part of which is shown at 5, Fig. 1.

13 represents a tucker, which is preferably a resilient blade attached at its inner 65 end to the frame of the machine and having its outer end terminating immediately adjacent to the lower end of the nailing block, as indicated in Fig. 1. The tucker is shown in Fig. 3 in plan view as adjustably longitudinally secured to the table of the machine by 70 the ordinary slot and bolt connection 20, 21.

The juxtaposition of the nailing block and the tucker is such, (see Fig. 3), that in order to present the heel-seat portion of the shoe 75 to the tack driver, the edges of the upper and counter at the convex portion of the heel-seat of the last, must be engaged by the end of the tucker 13, so that when a shoe is pressed in to the nailing block by 80 the hand of the operator, the surplus and loose material will be crowded in and pushed toward the medial line of the shoe. When the heel-seat has been made as narrow 85 as practical on one side of the shoe, the tack is driven, the shoe is reversed and the heel-seat narrowed on the opposite side and secured by the tack. I have found by actual measurement that I can make the heel-seats an eighth of an inch narrower adjacent to 90 the welt by this means. The result is that the upper and counter conform snugly to the shank of the last and a very narrow heel-seat is formed, so that the shoe is not only 95 better shaped, but in the subsequent operations the stitching is not damaged by the sole trimmer.

As will be seen from Fig. 3, the outer or working end of the blade 13 is wide enough to engage a substantial portion of the material to be tightened. The end of the blade is thin, and as will be readily understood by the ordinary welt operator, the juxtaposition of the blade and driver permit the shoe to be engaged between the welt 105 and upper, in position to engage the adjacent stitches in stretching the upper inwardly over the last.

Having described my invention, I claim:—

1. A machine for gathering in and hold-

110

- ing the upper and counter at the inner ends of the heel seats of a welt shoe while they are being tacked, consisting of a tacking device, and a resilient tucker blade, the free 5 end of which lies under and immediately adjacent to the tack driver in position to push inwardly the material to be tacked as the shoe is presented by the hand of the operator, substantially as described.
- 10 2. A machine for gathering in and holding the upper and counter at the inner ends of the heel seats of a welt shoe while they are being tacked, consisting of a tacking device, and a resilient tucker blade, the inner 15 end of which is supported by the frame of the machine, and the outer end of which lies under and immediately adjacent to the tack driver in position to push inwardly the material to be tacked when the shoe is presented 20 by the hand of the operator, substantially as described.
3. A machine of the class described, comprising a projecting arm secured to the machine and adjustable lengthwise, and tacking 25 mechanism, the engaging end of said arm and the delivery point of said tacking mechanism approximately coinciding, said engaging end of the arm being in position to permit a lasted shoe upper and welt to be 30 pushed thereover for stretching a loose portion of the upper tightly over a last in position to receive a tack from said tacking mechanism while so held stretched.
4. A machine for gathering in and holding 35 the upper of a lasted welt shoe at the inner ends of the heel seats while they are being tacked, consisting of a tacking device, a frame, and a resilient arm mounted on the frame, the free end of said arm being in 40 position to permit a lasted shoe upper and welt to be pushed thereover for stretching the upper over a last in position to receive a tack from said tacking mechanism while so held stretched.
- 45 5. A machine of the class described, comprising stationary positioning means to engage the shoe between the welt and upper in position to press against the adjacent line of stitches and stretch the upper over the last, 50 and means for driving a tack to retain the upper while held thus stretched.
6. A machine of the class described, comprising a projecting arm secured to the machine, having a thin wide end shaped and 55 arranged to engage the upper beneath the welt, and tacking mechanism including a
- nozzle, said engaging end of the arm being located immediately below and approximately in line with the tack delivering end of said nozzle.
7. A machine of the class described, comprising a positioning member having an engaging end to enter beneath the welt to press the upper forward over the last, said end being unyielding to forward pressure of the 60 shoe and yielding to vertical pressure of the shoe, and tack-delivering means located approximately in vertical alinement with the extremity of said engaging end of said member.
8. In a machine for working over a last the portion of shoe stock adjacent to the ends of the inseam, means for engaging the shoe in the welt crease to tighten the upper over the last, said means being constructed 70 and arranged for automatic movement upwardly under lengthwise pressure against it.
9. In a machine for working an upper over a last, a lasting device for engaging the shoe stock in the welt crease, combined with 75 tack-driving means, said lasting device being constructed and arranged to move the shoe automatically toward the tack-driving means when pressure is applied in the direction for forcing the upper over the last.
10. In a machine of the class described, tack-driving means, combined with a lasting device located below the tack-driving means and comprising a spring arm adapted to engage a welted shoe in the welt crease and 80 constructed and arranged to lift the shoe toward the tacking means by the pressure applied in forcing the upper into the lasted position.
11. A machine of the class described, 85 having, in combination, a tacker, and means for working into lasted position the upper of a welted shoe adjacent to the end of the inseam and the end of the row of heel seat tacks, said means being constructed and arranged to engage the shoe stock between the upper and the welt and force the upper inwardly over the edge of the last and upwardly toward the tacker and to hold the upper under tension while it is fastened by the 90 tacker.
- In testimony whereof, I have hereunto set my hand.
